DEFROSTING REFRIGERATION APPARATUS

Graham S. McCloy, Springfield, Mass., assignor
to Westinghouse Electric Corporation, East
Pittsburgh, Pa., a corporation of Pennsylvania

Application July 27, 1951, Serial No. 238,935

6 Claims. (Cl. 62—116)

1

This invention relates to refrigerating apparatus and more particularly to means for effectively defrosting such apparatus.

In some refrigerating systems on the market today the evaporator of the system is defrosted by circulating warm refrigerant through the system while maintaining the suction pressure in the system high enough to prevent evaporation of the refrigerant flowing through the evaporator. Since the evaporator is usually positioned adjacent portions of the cabinet structure, these portions are cooled to below 32° F. by the evaporator during the refrigerating operation and hence collect frost. During a defrosting operation, these frost collecting portions of the cabinet structure may not be warmed sufficiently to melt the frost collected thereon. The result is an objectionable progressive build-up of the frost which must be removed by hand.

It is accordingly an object of my invention to effectively defrost portions of the refrigerator cabinet structure which, because of their proximity to the evaporator, collect frost during the refrigerating operation.

Another object of my invention is to accomplish defrosting of these frost-collecting portions of the cabinet structure by the same means utilized to defrost the evaporator portion of the refrigerating system.

In certain present day refrigerators, a cooling unit is provided as a portion of the cabinet structure; which cooling unit serves as a sharp freezing chamber for the storage of ice and frozen foods. The cooling unit in this type of refrigerator is generally a boxlike structure having refrigerant passages formed in one or more walls thereof. While all portions of the cooling unit will be cooled below 32° F. during the refrigerating operation of the system, and consequently collect frost, those portions of the cooling unit which do not carry refrigerant will not be warmed sufficiently during the defrosting operation to melt the frost which may have collected thereon.

It is accordingly another object of my invention to effectively defrost all portions of a refrigerator cooling unit.

It is a further object of my invention to provide a novel cooling unit for mechanical refrigerators which may be quickly and effectively defrosted.

Another portion of the refrigerator cabinet structure which might fall into the above classification is the drip pan and its associated drain which is generally positioned beneath the evaporator or cooling unit to carry away defrost water

2

during the defrosting operation. Occasionally pieces of ice will be melted loose from the evaporator or cooling unit to fall into the drip pan and remain there even after the evaporator has been completely defrosted. During the subsequent refrigerating operation, the drip pan, because of its proximity to the evaporator, will be cooled sufficiently to maintain this ice in a hardened condition as well as to freeze any defrost water which may have remained in the drip pan. This ice build-up sometimes progresses to the point where the drain becomes completely clogged and water overflows from the drip pan during the next defrosting operation.

It is accordingly another object of my invention to raise the temperature of the evaporator drip pan above freezing during the period when the evaporator or cooling unit of the refrigerator is being defrosted.

These and other objects are effected by my invention as will be apparent from the following description and claims taken in connection with the accompanying drawings, forming a part of this application, in which:

Fig. 1 is a vertical sectional view of a refrigerator embodying this invention;

Fig. 2 is a front elevation of the novel cooling unit employed in this invention;

Fig. 3 is an exploded view of the cooling unit shown in Fig. 2;

Fig. 4 is a sectional view of the storage vessel employed in this invention; and

Fig. 5 is a partial vertical sectional view of a refrigerator embodying a modification of this invention.

Referring to the drawings for a description of the invention, the reference numeral 10 designates generally a refrigerator cabinet structure having a food storage chamber 12 in the upper portion thereof and a machine compartment 14 below the food storage chamber. The food storage chamber 12 is surrounded by thermal insulation 15 and has an access opening 16 in the front thereof closed by the door 17. A sealed casing 18 in the machine compartment 14 contains a compressor 20 and an electric motor 22 for driving the compressor. An inlet port 24 of the compressor 20 communicates with the interior of the sealed casing 18. A pressure conduit 26 conducts the refrigerant vapor compressed by the compressor 20 to an air cooled condenser 28 wherein it is cooled and condensed. A liquid line 30 including a capillary tube 32 conducts the refrigerant liquid formed in the condenser 28 to a storage vessel 34 located in

the upper portion of the food storage chamber 12, and forming a part of the rapid defrosting apparatus of the refrigerator.

Conduit means 36 are provided for conducting refrigerant liquid and vapor from the storage vessel 34 to the cooling unit 38. As best shown in Fig. 4, the conduit means 36 communicates through one end 39 thereof with a lower portion of the storage vessel 34 and extends upwardly through the top of the vessel 34 and has an elevated portion 40 positioned above the refrigerant liquid within the vessel 34. The conduit means 36 then extends downwardly through the storage vessel 34 and to the cooling unit 38. Restrictor means including an orifice 42 in the conduit means 36 provides communication between an upper portion of the storage vessel 34 and that portion of the conduit means 36 extending downwardly through the storage vessel 34. The conduit means 36 also has, in accordance with this invention, a heat exchanging portion 44 between the elevated portion 40 and the orifice 42. This heat exchanging portion is arranged in heat transfer relationship with portions of the cooling unit 38, the purpose of which will hereinafter be described.

The cooling unit 38 consists of a generally box like structure having a top wall 46, back wall 48, side walls 50, and a bottom wall 52. The cooling unit 38 is suspended within the upper portion of the food storage chamber 12 by suitable means such as brackets 54. The cooling unit 38 defines a sharp freezing chamber 56 having an access opening 57 in the front thereof which is closed by a movable door 58 pivoted at 60 for swinging movement downwardly.

Referring to Fig. 3, a generally U-shaped sheet metal evaporator 62 having refrigerant passages 64 formed therein forms the side walls 50 and bottom wall 52 of the cooling unit 38. The cooling unit 38 has a shelf 66 mounted therein which is provided with refrigerant passages 68 and is adapted to support ice trays 69 or the like within the sharp freezing chamber 56. The refrigerant passages 64 of the evaporator 62 and the refrigerant passages 68 of the shelf 66 are connected in series by means of a conduit 70.

The top wall 46 and the back wall 48 of the cooling unit 38 are formed of a generally L-shaped metal sheet 72 to which the serpentine heat exchanging portion 44 of the conduit means 36 is secured.

A suction conduit 74 conducts the vaporized refrigerant from the evaporator 62 downwardly to the motor compressor casing 18. The suction conduit 74 has a portion 76 thereof in heat-transfer relationship with a portion 78 of the capillary tube 32 and a second portion 80 in heat-transfer relationship with the pressure conduit 26.

The electric motor 22 receives its power from lines 82 through the leads 83, one of which is connected in series with a conventional thermostatic switch 84. The switch 84 is opened and closed in response to pressure changes within a temperature sensitive bulb 86 mounted on the blind tube 88 extending upwardly from the storage vessel 34. The switch 84, with its associated temperature sensitive bulb 86, controls the motor 22 to maintain the temperature of the cooling unit 38 at a substantially constant value near 0° F. The function and operation of the blind tube 88 is more fully described and claimed in the copending application of Graham S. McCloy, Serial No. 146,960, now Patent No. 2,645,094, July 75

14, 1953, filed March 1, 1950 and forms no part of the present invention.

A heater 90 is arranged in heat-exchange relationship with a portion of the liquid line 30 adjacent the storage vessel 34 and is energized by a suitable switch mechanism indicated generally at 92 through leads 94 which are preferably connected in parallel with the leads 83 and controlled by the switch 84. While any suitable switch mechanism may be employed for the control of heater 90, it is preferred that a switch mechanism 92 of the type described and claimed in patent application, Serial No. 143,788 now Patent No. 2,595,967 May 6, 1952 filed February 11, 1950 by the inventor of this invention be used. This mechanism includes a counting device which is actuated through the plunger 96 each time the door 17 is opened and closed. The switch mechanism 92 is so constructed as to energize the heater 90 when the refrigerator door 17 has been opened and closed a predetermined number of times such as, for example, sixty times. Deenergization of the heater is effected in response to a predetermined high temperature of the evaporator or its outlet conduit. As shown, a thermal responsive member 104 is associated with the switch mechanism 92 and responds to the temperature of the evaporator.

The operation of the above described apparatus is, in many respects, similar to the system described and claimed in Patent No. 2,459,173 issued January 13, 1949 to the inventor of this invention and is as follows: During the refrigerating operation, liquid refrigerant conveyed from the condenser 28 by the liquid line 30 accumulates in the storage vessel 34 and spills over through the orifice 42 into the conduit means 36 through which it is conveyed to the evaporator 62 entering first the refrigerant passages 68 in the refrigerated shelf 66 and then flowing through the refrigerant passages 64 in the U-shaped portion of the evaporator 62. The liquid refrigerant evaporates at relatively low pressure in the passages 68 and 64 and the gaseous refrigerant is withdrawn through the suction conduit 74 by the motor-driven compressor 20 for compression and condensation in the condenser 28.

Because of some vaporization within the vessel 34 and the delivery of some flash gas to the vessel 34 by the capillary tube 32, a pressure drop across the orifice 42 is produced. This pressure drop is predetermined by the size of the orifice 42 and is effective to deliver the proper amount of liquid refrigerant to the conduit means 36 for passage to the evaporator 62. Of course, this pressure drop will tend to force liquid upwardly in the elevated portion 40 of the conduit means but it is insufficient to force the liquid, in opposition to the head thereof, beyond the portion 40 into the heat exchanging portion 44. The effect is to bypass the heat exchanging portion 44 of the conduit means 36 and, consequently, this portion 44 of the conduit means 36 and the top 46 and back 48 of the cooling unit 38 secured thereto are not directly cooled by vaporizing refrigerant. However, the top 46 and back 48 of the cooling unit 38 are cooled sufficiently to collect frost because of their proximity to the evaporator portion 62 of the cooling unit 38.

To effect defrosting of the cooling unit 38, the heater 90 is energized by the closing of switch mechanism 92. Since the switch mechanism 92 is in series with motor switch 84, energization of the heater 90 is effected only during periods

of operation of the motor and compressor. The heat supplied by the heater 90 vaporizes a major portion of the refrigerant liquid flowing through the line 30. The increased quantity of gaseous refrigerant conveyed to the vessel 34 increases the pressure drop across the orifice 42 to a value greater than the static head of the refrigerant liquid contained in the elevated portion 40 of the conduit means 36. As a result, liquid refrigerant is forced out of the vessel 34 through the elevated portion 40 of the conduit means 36 to the heat exchanging portion 44 thereof and thence to the evaporator 62. The liquid refrigerant thus forced out of the vessel 34 floods the refrigerant passages 68 of the shelf 66 and the refrigerant passages 64 of the evaporator 62 and overflows into the suction conduit 74.

The hot refrigerant vapor in the pressure conduit 26 vaporizes refrigerant liquid in the portion 80 of the suction conduit 74 and thereby raises the suction pressure in the conduit 74 and in the evaporator 62. The heater 90 continues to vaporize a major portion of the refrigerant liquid flowing through line 30; the vaporous refrigerant passing through the vessel 34 into the unrestricted end 39 of conduit means 36. The hot refrigerant vapor condenses in the heat exchanging portion 44 of the conduit means 36 and in the evaporator 62, transferring the latent heat to these members for the melting of frost therefrom.

Water formed by the melting of frost from the cooling unit 38 falls into a drip pan 98 positioned beneath the cooling unit 38 and is conducted, by means of a drain tube 100, to an evaporating tray 102 in the machinery compartment 14 where it is evaporated by heat from the condensing machinery. The defrosting operation is terminated by the switch mechanism 92 which deenergizes the heater 90 in response to a predetermined high temperature of the cooling unit 38 as sensed by the thermo-sensitive bulb 104.

The modification of the invention shown in Fig. 5 is similar to the embodiment described and parts common to both embodiments are indicated by similar reference characters. The only difference in these embodiments resides in the disposition and function of the heat exchanging portion of the conduit means 36. As shown in Fig. 5, the heating exchanging portion of the conduit means 36 is indicated at 106 and is connected in heat transfer relationship with the drip pan 98 in order to heat it to a temperature above freezing during a defrosting cycle. The heat exchanging portion 106 of Fig. 5 is connected in the conduit means 36 and to the vessel 34 in exactly the same manner as the heat exchanging portion 44 of Fig. 1 and the refrigerating and defrosting operations of the two embodiments are similar.

From the foregoing description, it will be apparent that I have provided an improved refrigerating system having provisions for defrosting the evaporator thereof by the circulating of heated refrigerant through the evaporator and wherein parts of the refrigerator structure subject to frosting may be heated by the heated refrigerant during a defrosting cycle and without directly subjecting such parts to liquified refrigerant during a refrigerating cycle.

While I have shown my invention in several forms, it will be obvious to those skilled in the art that it is not so limited, but is susceptible of various other changes and modifications without departing from the spirit thereof.

What I claim is:

1. In refrigeration apparatus, the combination of an insulated cabinet structure enclosing a food storage chamber and including an evaporator disposed within said chamber for cooling media therein, a closed refrigerant circuit for conveying refrigerant to and from said evaporator, said circuit comprising a compressor, a suction conduit for conveying refrigerant from said evaporator to said compressor, a condenser for condensing refrigerant vapor compressed by said compressor, a storage vessel for selectively trapping or releasing refrigerant liquid, a liquid line including a restrictor for conveying refrigerant from said condenser to said vessel, first conduit means connecting a lower portion of said vessel with said evaporator, said first conduit means having a portion thereof elevated with respect to the liquid level in said vessel, second conduit means connecting an upper portion of said vessel with said evaporator, said second conduit means having a restriction therein, said restriction being of a size sufficient to pass all of the refrigerant flowing to said evaporator during the refrigerating operation of said circuit, and means for heating the refrigerant in said vessel to increase the vapor pressure in said vessel whereby refrigerant liquid and vapor is forced from said vessel to said evaporator through said first conduit means to effect defrosting of said evaporator, said first conduit means having a portion thereof in heat exchange relationship with a portion of said cabinet structure cooled by said evaporator whereby the warm refrigerant flowing through said first conduit means defrosts that portion of said cabinet structure.

2. In refrigeration apparatus, the combination of an insulated cabinet structure defining a food storage chamber and including an evaporator disposed within said chamber for cooling the media therein, said evaporator cooling portions of said cabinet structure adjacent thereto below 32° F. whereby frost collects thereon, a closed refrigerant circuit for conveying refrigerant to and from said evaporator, said circuit comprising a compressor, a suction conduit for conveying refrigerant from said evaporator to said compressor, a condenser for condensing refrigerant vapor compressed by said compressor, a storage vessel for selectively trapping or releasing refrigerant liquid, a liquid line including a restrictor for conveying refrigerant from said condenser to said vessel, conduit means connecting a lower portion of said vessel with said evaporator, said conduit means having a portion thereof elevated with respect to the liquid level in said vessel, restrictor means including an orifice connecting an upper portion of said vessel with said conduit means at a point between said elevated portion and said evaporator, said restrictor means permitting refrigerant flowing from said vessel to said evaporator to bypass the elevated portion of said conduit means during the refrigerating operation of said circuit, said conduit means having a portion thereof between said elevated portion and said orifice in heat exchange relationship with said frost-collecting portions of said cabinet structure, and means for heating the refrigerant in said vessel to increase the vapor pressure in said vessel whereby refrigerant liquid and vapor is forced from said vessel through the elevated portion of said conduit means to said evaporator to effect defrosting of said evaporator and said frost-collecting portions of said cabinet structure.

3. In refrigerating apparatus, the combination

with a cooling unit defining a freezing compartment and comprising a generally U-shaped, sheet metal evaporator structure having refrigerant passages formed therein, said evaporator forming side and bottom walls of said cooling unit and a generally L-shaped sheet member forming the top and back walls of said cooling unit, of a conduit secured in heat exchange relationship with portions of said L-shaped member, refrigerant circulating means including compressing and condensing apparatus for supplying liquid refrigerant at low pressure to the refrigerant passages of said evaporator alone to effect refrigeration of said cooling unit and means for modifying the operation of said refrigerant circulating means to supply refrigerant at a higher pressure to both said conduit and said evaporator to effect defrosting of said cooling unit.

4. Refrigerating apparatus as claimed in claim 3, including means for heating the higher pressure refrigerant supplied to said conduit and said evaporator structure to effect defrosting of said cooling unit.

5. In refrigeration apparatus, the combination of an insulated cabinet structure defining a food storage chamber, a cooling unit disposed within said chamber and defining a freezing compartment, said cooling unit comprising a generally U-shaped, sheet metal evaporator structure having refrigerant passages formed therein, said evaporator structure forming side and bottom walls of said unit, and a generally L-shaped sheet member forming the top and back walls of said cooling unit, a closed refrigerant circuit for conveying refrigerant to and from said evaporator, said circuit comprising a compressor, a suction conduit for conveying refrigerant from said evaporator to said compressor, a condenser for condensing refrigerant vapor compressed by said compressor, a storage vessel for selectively trapping or releasing refrigerant liquid, a liquid line including a restrictor for conveying refrigerant from said condenser to said vessel, conduit means connecting a lower portion of said vessel with said evaporator, said conduit means having a portion thereof elevated with respect to the liquid level in said vessel, restrictor means including an orifice connecting an upper portion of said vessel with said conduit means at a point between said elevated portion and said evaporator, said restrictor means permitting refrigerant flowing from said vessel to said evaporator to bypass the elevated portion of said conduit means during the refrigerating operation of said circuit, said

10
15

conduit means having a portion thereof between said elevated portion and said orifice in heat exchange relationship with said L-shaped sheet member, and means for heating the refrigerant in said vessel to increase the vapor pressure in said vessel whereby the refrigerant liquid and vapor is forced from said vessel through the elevated portion of said conduit means to said evaporator to effect defrosting of said cooling unit.

6. In refrigeration apparatus, the combination of an insulated cabinet structure defining a food storage chamber, an evaporator disposed within said chamber for cooling the media therein, a closed refrigerant circuit for conveying refrigerant to and from said evaporator, said circuit comprising a compressor, a suction conduit for conveying refrigerant from said evaporator to said compressor, a condenser for condensing refrigerant vapor compressed by said compressor, a storage vessel for selectively trapping or releasing refrigerant liquid, a liquid line including a restrictor for conveying refrigerant from said condenser to said vessel, conduit means connecting a lower portion of said vessel with said evaporator, said conduit means having a portion thereof elevated with respect to the liquid level in said vessel, restrictor means including an orifice connecting an upper portion of said vessel with said conduit means at a point between said elevated portion and said evaporator, said restrictor means permitting refrigerant flowing from said vessel to said evaporator to bypass the elevated portion of said conduit means during the refrigerating operation of said circuit, means for heating the refrigerant in said vessel to increase the vapor pressure in said vessel whereby refrigerant liquid and vapor is forced from said vessel through the elevated portion of said conduit means to said evaporator to effect defrosting of said evaporator, and a drip pan and drain positioned beneath said evaporator for catching and disposing of the water during the defrosting of said evaporator, said conduit means having a portion thereof between said elevated portion and said orifice arranged in heat exchange relationship with said drip pan whereby said drip pan is warmed when said evaporator is defrosted.
